UNITED STATES PATENT OFFICE.

GEORGE C. HARRISON, OF ELYRIA, OHIO.

BAG-HOLDER.

1,055,745.

Specification of Letters Patent. Patented Mar. 11, 1913.

Application filed October 5, 1910. Serial No. 585,506.

To all whom it may concern:

Be it known that I, GEORGE C. HARRISON, citizen of the United States, residing at Elyria, in the county of Lorain and State 5 of Ohio, have invented certain new and useful Improvements in Bag-Holders, of which the following is a specification.

My invention relates to clamping devices whereby a member may be supported upon 10 a standard at any desired height thereon and easily detached from its locked engagement with the standard so as to permit it to be shifted up and down on the standard, and while the clamping device forming the 15 subject-matter of this invention is particularly adapted to bag holders, I do not wish to be limited to this application of the invention.

Figure 1 is a perspective view of my improved bag holder. Fig. 2 is a detail fragmentary elevation partly in section of the standard and the bag support.

Referring to these figures 2 designates a standard formed of iron pipe of any suitable height. The lower end of the standard is screw threaded and engaged with a T 3, which in turn engages with the laterally extending pipes 4 forming the cross bar of the standard. These pipes 4 at their ends have 30 screw threaded engagement with the T's 5, and engaged with the ends of the T's 5 are the pipes 6 and 7, these pipes being provided at their ends with the elbows 8 forming the feet of the base.

Shiftably mounted upon the standard is the transversely extending bar 9 whose ends are angularly bent as at 10 and form spreaders for the bag to hold it open. In order to engage the bag upon the spreaders I provide the angular members 11, each of which has the outwardly projecting flange 12 which extends over the upper edge of the angular terminations 10 of the bar 9. These angular portions 12 of the strips 11 not only project 45 over and beyond the faces of the terminations 10 but also project rearward as at 13. The relatively sharp edges of the flanges 12 and the projecting portion 13 engage with the material of the bag and hold it firmly 50 upon the bar 9. The bar 9 is secured upon a sliding head 14 having the longitudinally extending elongated slot 15 on its rear end. The head has the downwardly extending bill 16 upon its forward end whose inner 55 face is coincident with the front end of the slot 15. The standard 2 passes up through this slot 15 and the inner face of the bill 16 contacts with the standard 2. The forward end of the head 14 is transversely extended as at 17 and is held to the bar 9 by 60 bolts or nuts 18.

In order to hold the head 14 in sliding engagement with the standard 2 and yet permit the head to be locked or clamped at any desired point upon the standard 2, I 65 provide the locking device illustrated in Fig. 2 and consisting of a wedge 19 extending down through the slot 15 behind the standard, the upper edge of the wedge being provided with the outwardly extending 70 tail 20, the upper face of which is downwardly inclined. A coil spring 21 is disposed between the upper face of the head 14 and the under face of the tail 20, the head being formed with a socket in which the 75 lower end of the spring rests. That face of the wedging member 19 which engages with the standard 2 has a straight portion 22 and is then cut away as at 23, it having another slightly inclined portion 24 below this cut 80 away part 23. The outer face of the wedging member 19 is outwardly and downwardly inclined as at 25, the face being slightly curved. The outer end wall of the slot 15 is upwardly and inwardly inclined 85 toward the standard 2 and this upwardly and inwardly inclined face engages with the outwardly and downwardly inclined face 25 of the wedging member. Thus as the wedging member is drawn upward it will be wedged 90 into clamping engagement with the standard 2, while when it is forced downward it will be released from said clamping engagement and shifted laterally a sufficient distance to permit the head 14 to be easily slipped up and 95 down upon the standard. The spring 21 of course acts to shift the wedging member upward and into its clamping engagement, and by pressing downward upon the tail 20 and compressing the spring, the wedging 100 member is moved downward and out of its clamping engagement so that the head may be easily shifted. By then releasing the tail the spring 21 will throw the wedging member into its clamping engagement. While 105 the means so described will hold the head set or clamped in any vertically adjustable position, it will not prevent the head from rotating upon the standard, and to the end that the head may be held from rotation 110 after it has been set, I provide the set screw 26 which passes through the rear end of the

head and engages with the outer face of the wedging member 19. When this set screw is turned inward it forces the wedging member into tight engagement with the standard and prevents any rotation of the head and the bag support. It will be seen that the upward movement of the wedging member 19 tends, not only to move the head laterally, but also tends to lock the bill 16 against the standard so that any downward pressure on the bag holder will be supported by this bill 16, this bill forming a bracket and giving a more extended bearing to the bag support and head, thus preventing the head from yielding even slightly when the bag is filled.

In order to prevent the head from being removed from the standard, I screw thread the upper end of the standard as at 27 and engage therewith a cap 28. Disposed below this cap 28 and held in position by the cap, is the knife blade 29, the outer edge of which is inclined, this inclined edge and the upper edge being sharpened. This knife blade 29 is inserted in a slot formed in the upper end of the standard. After the bag has been filled and tied, the cord may be easily cut by raising the bag and bringing the cord in contact, either with the upper or inclined face of the knife blade. It will be seen from Fig. 2 that the wedging member 19 projects above the upper face of the head 14 and that when the head 14 is moved upward to its full extent, the upper end of the wedging member will contact with the cap 28 before the upper face of the head can contact with the knife blade 29. As a consequence there will be no danger in moving the head upward or blunting the edge of the knife.

In order to provide a support for the bag

I mount upon the outwardly extending legs 7 the flat cross bar 30. This cross bar at its ends is upwardly bent and curved over the pipes forming the legs 7 and is attached to these legs by means of the bolts 31 which pass downward through the legs.

What I claim is:

The combination with a standard, of a head having an elongated slot through which the standard passes, the rear end of the slot being upwardly and inwardly inclined, a wedging member located in the slot and projecting beyond the same at both ends, the outer face of said wedging member being outwardly and downwardly inclined, the upper portion of the inner face of the wedging member conforming approximately to the standard, the intermediate portion of the wedging member being cut away and the lower portion of the wedging member having its inner face upwardly and outwardly inclined to form an angularly disposed lower terminal bearing against the standard and spacing the intermediate portion of the wedging member therefrom, the upper end of the wedging member being formed with an outwardly and downwardly projecting tail providing means whereby the wedging member may be manipulated, a spring supported in a socket in the upper face of the head and engaging the end face of said tail and housed by the tail, and a set screw passing through the head and engaging the wedging member to force it into binding contact with the standard.

In testimony whereof I affix my signature in presence of two witnesses.

GEORGE C. HARRISON. [L. s.]
